United States Patent Office

Des. 187,635
Patented Apr. 12, 1960

187,635

LAVATORY OR SIMILAR ARTICLE

Henry Dreyfuss, South Pasadena, Calif., assignor to Crane Co., Chicago, Ill., a corporation of Illinois

Application August 21, 1958, Serial No. 52,321

Term of patent 14 years

(Cl. D4—2)

Des. 187,635

PAGE 2

Fig. 3.

Fig. 4.

Fig. 5.

Fig. 6.

Fig. 1 is a plan view of a lavatory or similar article embodying my design;

Fig. 2 is a front view thereof;

Fig. 3 is a bottom view thereof;

Fig. 4 is a rear view thereof;

Fig. 5 is a side view thereof; and

Fig. 6 is a transverse sectional view taken along the line 6—6 in Fig. 2.

I claim:

The ornamental design for a lavatory or similar article, substantially as shown.
